Atty. 1121

UNITED STATES PATENT OFFICE.

GILMORE BUSS, OF SANDPOINT, IDAHO.

ROWING MACHINE.

Application filed February 28, 1925. Serial No. 12,270.

To all whom it may concern:

Be it known that I, GILMORE BUSS, a citizen of the United States, residing at Sandpoint, in the county of Bonner and 5 State of Idaho, have invented certain new and useful Improvements in Rowing Machines; and I do hereby declare the following to be a full, clear, and exact description of the invention, such as will enable others 10 skilled in the art to which it appertains to make and use the same.

The invention relates to means for propelling small boats commonly known as row boats, and has for its principal object the 15 provision of a propelling mechanism adapted to be mounted upon small boats of ordinary construction by which the propulsion of the boats may be simplified and made more efficient.

20 A further object of the invention is the provision of a rowing machine that is so constructed with paddle blades that the blades enter the water in a substantially vertical position and retain this position until they emerge from the water so that the 25 full force of the blades is exerted on the water throughout the length of the stroke.

The construction and advantages of the invention will be clearly described herein- 30 after and will be found illustrated in the accompanying drawings in which

Figure 1 is a view in perspective of the improved rowing machine showing it in 35 operation,

Figure 2 is a top plan view,

Figure 3 is a side view in elevation,

Figure 4 is a cross section on the plane indicated by the line 4—4 of Figure 2, and

40 Figure 5 is a cross section on the plane indicated by the line 5—5 of Figure 2.

In the drawings similar reference characters will be used to designate corresponding parts throughout the several views.

A boat is indicated at A on which the improved rowing machine is installed. The 45 rowing machine comprises two standards 1, one on each side of the boat a little forward of amidships, said standards being preferably formed as shown in the drawings of two bars secured to the sides of the boat and 50 having their upper portions diverging, and a plate or block 2 secured between the two arms. 3 indicates brace rods connecting the forward ends of the plate or block 2 to the

inner and outer sides of the boat, and 4 indicates a similar brace rod extending rearwardly of the block 2.

Other standards 5 similar in construction to the standards 1 are secured to the sides of the boat A near the stern and have plates 6 secured between the arms thereof and are braced by means of bars 7.

Journaled on plates 2 are crank shafts 8 that are actuated by cranks 9, and 10 indicates arms secured to the shafts 8 intermediate of their ends and having offset portions 11 on one of their ends and counter-weights 12 at their other ends.

13 indicates other arms journaled on plates 6 by means of an angular portion 14, and 15 indicates an offset portion at the free end of each arm 13.

On each side of the boat A is a bar 16 pivotally connected to the offset portions 11 and 15 of the arms 10 and 13 respectively, 75 and secured to the bar 16 is a paddle blade 17 adjacent the forward end of the bar and strengthened by means of braces 18.

The arms 13 are longer than that part of each arm 10 between shafts 8 and offset portions 11 so that when the shaft 8 is rotated in operating the boat the rear end of the bar 16 will oscillate. It will be apparent that in operating the machine the paddle blades 17 will enter the water in a substantially vertical position and will maintain a vertical position during the propelling stroke and leave the water in substantially the same position, thus adding to the efficiency of the propelling mechanism by exerting the full force of the paddle blade on the water throughout the entire stroke.

It will also be understood that the device will be operated by an operator facing the bow of the boat so that he is at all times facing the direction in which the boat is being propelled, and can readily steer the boat by proper manipulation of the propellers, each propelling mechanism being operated independently of the other.

100 What is claimed is:—

1. In a rowing machine, two arms pivotally mounted, one of said arms being shorter than the other, a bar pivotally connecting said arms, and a paddle blade secured to said 105 bar.

2. In a rowing machine, a rotatable shaft, an arm secured to said shaft, another arm

pivottally mounted and longer than the first mentioned arm, a bar connecting said arms, and a paddle blade secured to said bar.

3. In a rowing machine, a rotatable shaft, 5 a counterweighted arm secured to said shaft, another arm pivottally mounted and longer than the first mentioned arm, a bar pivottally connecting said arms, and a paddle blade secured to said bar adjacent the first 10 mentioned arm.

4. A rowing machine comprising in combination with a boat, standards mounted on said boat, a crank shaft journaled on one of said standards, an arm secured to said shaft 15 another arm, longer than the first mentioned arm, pivottally mounted on the other stand-

ard, a bar pivottally connecting said arms, and a paddle blade secured to said bar adjacent the first mentioned arm.

5. A rowing machine comprising in combination with a boat, standards mounted on said boat, a crank shaft journaled on one of said standards, an arm secured to said shaft intermediate of its ends, another arm longer than the first mentioned arm, pivottally mounted on the other standard, a bar pivottally connecting said arms, a paddle blade secured to said bar adjacent the first mentioned arm, and a counterweight on the free end of the first mentioned arm. 20 25 30

In testimony whereof I affix my signature.
GILMORE BUSS.
